UNITED STATES PATENT OFFICE.

JOHN ETTL, OF LEONIA, NEW JERSEY.

PANTOGRAPHIC APPARATUS FOR USE OF SCULPTORS.

1,037,460.

Specification of Letters Patent.

Patented Sept. 3, 1912.

Application filed November 17, 1911. Serial No. 660,765.

To all whom it may concern:

Be it known that I, JOHN ETTL, a citizen of the United States, residing at Leonia, in the county of Bergen and State of New Jersey, have invented certain new and useful Improvements in Pantographic Apparatus for Use of Sculptors, of which the following is a specification.

My improvements relate to means for producing statuary, &c., either upon the same, or an enlarged or reduced scale, as may be desired, and the main object is to afford a simple but effective apparatus which may be manipulated with convenience and accuracy.

The invention consists in the specific construction and arrangement of parts herein described and claimed, whereby I attain unrestricted scope and space both vertically and horizontally, and free and unrestricted access to all sides and parts of the model and work, as hereinafter fully set forth.

In the accompanying drawings, Figure 1, is a sectional elevation showing the essential features of my improved apparatus; Fig. 2, is a sectional detail of one of the indicators; and Fig. 3, a detail showing the ball and socket fulcrum.

An important desideratum in apparatus of this character, and one not heretofore attained in the art in so far as I am aware, is perfect and unrestricted accessibility to both model and work not only from above or vertically, but also on all sides, or horizontally in all directions. Furthermore both model and work should be accurately centralized with relation to their axes of rotation and with relation to each other and all parts should move synchronously and proportionately in order to attain perfectly accurate results. To attain these advantages I provide two turn tables A, B, rotatable upon and with axial spindles a, b, which are connected by any suitable mechanical expedient which will insure their movement in unison, as by means of the bevel gears 1, 2, 3 and 4 and the transmitting shaft 5, shown in Fig. 1.

While it is obvious that the apparatus may be used either simply for copying, or for enlarged or reduced reproductions, it is used in a majority of cases for the production of enlargements from a relatively small model, and for this reason I have in the present case, as a matter of convenience,

designated the larger turn table A, as the work table and the smaller turn table B, as the model holder. The larger or work table A, is provided on its under side with an annular grooved bearing piece a', concentric with the spindle a, and fitting over a correspondingly grooved and concentric bearing a², supported upon a suitable platform or frame work a³. The work turn table A, really rests upon a series of anti-friction rollers interposed in and between the grooved annular bearings a' and a², as indicated in Fig. 1. The spindle a, is secured rigidly to the work table A, as is also the miter gear 1. The pattern or model table B, is arranged at a prescribed distance from the axis of the work table A, dependent upon the size of reproduction desired. The spindle b, is mounted in such manner as to be vertically adjustable by any suitable means. Thus in the drawings said spindle is shown as provided with an adjustable collar b', resting upon the upper end of the bearing sleeve b², supported upon suitable arms b³, b⁴.

In Fig. 1, the parts are set, by way of illustration, for an enlargement equivalent approximately to ten to one, and the model table B, is raised so as to bring the medial horizontal line x, of the model into coincidence with that of the desired reproduction to be erected on the work table A. The lines y and z, represent respectively the extreme upper and lower limits of the scope of reproduction thus provided for.

What may be designated as the proportional or pantographic compass beam P, is supported at or near one extremity, (that nearest the pattern turn table B,) on a "universal" or ball and socket joint s, situated, in the illustration given in Fig. 1, a distance from the axial center of the table B, equivalent to one tenth the distance between said axial center and that of the work table A. The pointers or indicators i', i², are pivotally mounted at corresponding distances apart, on the pantographic beam P, their pivotal supports p', p² being arranged substantially in line vertically with the axes of the model table B, and of the work table A, respectively. These pivotal supports p', p², are situated on bracket arms p³, p⁴, which are adjustably mounted upon the pantographic beam P, which latter is preferably of square or other polygonal form in cross

section. As shown in the drawings the bracket arms p^3 , p^3 , are formed with clamping jaws p^4 , (see Fig. 2) by which they may be secured in a prescribed position on the beam P , or other mechanical expedients may be resorted to for the purpose with like result. The upper extensions i^{11} , i^{22} , of the indicators i' , i^2 , beyond the pivotal supports p' , p^2 , are coupled together by a connecting rod c , pivotally connected with said upper extensions i^{11} , i^{22} , so that the indicators i' , i^2 , necessarily move in unison during use,—said indicators i' , i^2 , being made of proportional relative lengths as measured from their pivotal supports p' , p^2 . In this connection it may be stated that the indicators i' , i^2 , may consist of light but rigid rods adjustable in tubular shanks i^3 , i^3 , extending below the pivotal supports p' , p^2 , and held in place by set screws i^4 , i^4 , or equivalent means, as may be found most expedient,—the said indicators, shanks and upper extensions constituting virtually rock levers pivotally supported on the pantographic beam and controlled to move in unison by the connecting rod c . On account of the length of the connecting rod c , I prefer to afford it additional support by the provision of one or more intermediate rods c' , pivotally connected with it and with one or more additional bracket arms p^3 , like unto those hereinbefore described, thus preventing the sagging of the connecting rod and insuring the proper parallelism of the indicators i' , i^2 .
As before stated the pantographic beam P , is fulcrumed at or near one extremity by a ball and socket joint s , the ball being attached to the lower end of a rod s' , which is adjustable in a bearing sleeve s^2 , attached to the clamp s^3 . The ball is held to its seat by springs s^4 , s^4 , (see Fig. 3) of sufficient tensile strength to prevent accidental displacement; and the pantographic beam P , is further supported by a counterweight w , through the medium of a suspender w' , passing over suitable pulley supports w^2 , w^2 , attached to stationary parts suitably situated above the apparatus to afford ample scope for the free and convenient manipulation thereof. By this construction and arrangement of parts it is obvious that the pantographic beam P , may be raised or lowered vertically or inclined and turned at any angle transversely practically from a vertical to a horizontal position. That is to say the ball rod s' , may be inclined in any direction from and above a horizontal plane central with relation to the ball and socket or so-called "universal" joint, and hence access is afforded to any and all portions of the model and "work" above the planes of the respective tables. Furthermore the scope of the apparatus is absolutely free, unlimited and unobstructed above and on all sides, it being only necessary to make and adjust the parts

with relation to each other in accordance with the size, scope and requirements of the work to be done.

It is to be noted that in my construction and arrangement of parts as distinguished from the prior state of the art, provision is made for supporting both the pattern or "model" and the "work" axially upon the horizontal turn tables, and that the pantographic beam is supported vertically above said turn-tables and may be manipulated on either side thereof, so that both tables and reeling and indicating mechanism may be moved with relation to each other in such manner as to render every part of the model and work, no matter how delicate or intricate, fully and conveniently accessible; also that the indicators are pivotally mounted upon the pantographic beam, and while moving in unison have a freedom and adaptability not heretofore attained; and that the apparatus, considered as a whole is simple of structure and manipulation, and free from the objection of being "in its own way" i. e., in that it has no parts that interfere with or obstruct the freedom or scope of action of other parts.

It is to be understood that my apparatus is designed solely for the use of sculptors and their assistants in the plastic reproduction of relief work, either enlarged or reduced, from a model. In producing an enlargement the small model is centered and secured upon the turn table B , and a suitable basic frame work is built upon and secured to the work turn table A ,—said basic frame work being covered with a suitable layer of plastic material which is built up and molded according to measurements transmitted from the pivoted feeling indicator i' , through the medium of the connecting rod c , to the pivoted indicator i^2 , which travels in unison with the feeler i' . If a reduction is required the operation is essentially reversed with like result.

What I claim as my invention and desire to secure by Letters Patent is,

1. In apparatus of the character designated, the combination of a model turn-table, and a work turn-table, connecting means adapted to cause them to rotate synchronously, a pantographic beam mounted above said turn-tables, a ball and socket joint supporting one extremity of said pantographic beam, a counterweighted suspender supporting the other extremity of said pantographic beam, indicators pivotally mounted on said pantographic beam, and a connecting rod pivotally attached to said indicators, for the purpose and substantially in the manner set forth.

2. In apparatus of the character designated, the combination of a model turn-table, means for adjusting the same vertically, a work turn-table, connecting means

adapted to cause said turn-tables to rotate synchronously, a pantographic beam mounted above said turn-tables, a ball and socket joint supporting one extremity of said 5 pantographic beam, a counterweighted suspender supporting the other extremity of said pantographic beam, indicators pivotally mounted on said pantographic beam, and a connecting rod pivotally attached to 10 said indicators, for the purpose and substantially in the manner set forth.

3. In apparatus of the character designated, the combination of a model turn-table, a work turn-table, a transmitting 15 shaft and gearing connecting said turn-tables and adapted to cause them to rotate synchronously, a pantographic beam mounted above said turn-tables, a ball and socket joint supporting one extremity of said 20 pantographic beam, a counterweighted suspender supporting the other extremity of said pantographic beam, indicators pivotally mounted on said pantographic beam, and a connecting rod pivotally attached to said 25 indicators, for the purpose and substantially in the manner set forth.

4. In apparatus of the character designated, the combination of a model turn-table, and a work turn-table, connecting 30 means adapted to cause said tables to rotate synchronously, a pantographic beam mounted above said turn-tables, a ball and socket joint supporting one extremity of said 35 pantographic beam, a counterweighted suspender supporting the other extremity of said pantographic beam, adjustable bracket arms on said pantographic beam, indicators pivotally mounted on said bracket arms, and a connecting rod pivotally attached to said 40 indicators, for the purpose and substantially in the manner described.

5. In apparatus of the character designated, the combination of a model turn-table and a work turn-table, connecting 45 means adapted to cause said tables to rotate synchronously, a pantographic beam mounted above said turn-tables, said beam

being of angular cross section, a ball and socket joint supporting one extremity of said pantographic beam, a counterweighted suspender supporting the other extremity of said beam, bracket arms on said beam formed with clamps for securing the bracket arms adjustably on said beam, indicators pivotally mounted on said bracket arms, and a connecting rod pivotally attached to said 55 indicator, for the purpose and substantially in the manner described.

6. In apparatus of the character designated, the combination of a model turn-table, and a work turn-table, connecting 60 means adapted to cause said tables to rotate synchronously, a pantographic beam mounted above said turn-tables, a ball and socket joint supporting one extremity of 65 said pantographic beam, a counterweighted suspender supporting the other extremity of said pantographic beam, adjustable bracket arms on said pantographic beam, indicators pivotally mounted on said bracket arms, a connecting rod pivotally attached to said 70 indicators, an intermediate bracket arm on said beam, and a supporting rod pivotally connected with said intermediate bracket arm and said connecting rod, for the purpose and substantially in the manner set forth.

7. In apparatus of the character designated, the combination of a model turn-table, and a work turn-table, connecting 75 means adapted to cause them to rotate synchronously, a pantographic beam mounted above said turn-tables, a ball and socket joint supporting one extremity of said 80 pantographic beam, a counterweighted suspender supporting the other extremity of said pantographic beam, and indicators pivotally mounted on said pantographic beam, for the purpose and substantially in the manner set forth.

JOHN ETTL.
